UNITED STATES PATENT OFFICE.

JOHN RICHARD DE MIER, OF LAS CRUCES, TERRITORY OF NEW MEXICO,
ASSIGNOR, BY MESNE ASSIGNMENTS, TO THE DE MIER ELECTRIC TRAIN
SIGNAL COMPANY.

ELECTRIC SIGNAL FOR RAILWAY-CARS.

SPECIFICATION forming part of Letters Patent No. 380,647, dated April 3, 1888.

Application filed June 9, 1887. Serial No. 240,780. (No model.)

To all whom it may concern:

Be it known that I, JOHN RICHARD DE MIER, a citizen of the United States, residing at Las Cruces, in the county of Doña Aña, Territory of New Mexico, have invented certain new and useful Improvements in Electric Signals for Railroad-Cars; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an electric open-circuit apparatus for giving signals to the engineer and other persons in charge of a train, said apparatus being made in sections suitably coupled.

20 My invention has for its object the production of an automatic and manipulative open-circuit electric signaling apparatus which can be quickly and easily applied to a train of cars while the train is being made up, or put 25 in position previous to its departure from the railroad-station, and which can with equal facility be removed therefrom accordingly as circumstances may require.

25 My invention consists in certain novel constructions, arrangements, and combinations of parts, as will be hereinafter described and claimed.

30 In the accompanying drawings, Figure 1 is a side view of a locomotive, tender, and passenger-car provided with my invention, portions of the car-body being broken away to show circuit-closer and circuit-coupler. Fig. 2 is a view showing a battery and alarm-bell used therewith. Fig. 3 is a perspective view 35 of a portion of the circuit-coupling of my apparatus, which is fastened to the outside of the end of a car; and Fig. 4 is a perspective view of the sliding portion of said coupling. Fig. 5 is a top view of the coupling portions as 40 united for service. Fig. 6 is a central longitudinal section of one of the sliding portions of said coupling and a portion of the part shown in Fig. 3. Fig. 7 is a transverse section in the line $x-x$ of Fig. 5 of the coupling 45 united. Fig. 8 is a transverse section in the

same line when the sliding portion of the coupling is partly moved out of the fixed portion shown in Fig. 3. Fig. 9 is a transverse section in the line $y-y$ of Fig. 5. Fig. 10 is a longitudinal central section of a circuit-closer 55 shown in Fig. 1, operated by the bell-rope of a car. Fig. 11 is a view of the same mounted in a car and of the operating-handles, and Fig. 12 is a front view and Fig. 13 a side view of one of the said handles. Fig. 14 is a modified 60 construction of the circuit-closer shown in Fig. 10. Fig. 15 is a horizontal central section and a partial elevation of another modified construction of the said circuit-closer. Fig. 16 is a side elevation of the same. Fig. 65 17 is a view showing said circuit-closer mounted in a car. Fig. 18 is a vertical central section of a modified construction of the circuit-closer shown in Fig. 10, the same being adapted for use on freight-cars; and Fig. 19 is an enlarged 70 central section of the lower portion thereof. Fig. 20 represents a combined coupling and circuit-closer, the former partly in section and the latter wholly in section, and the same attached to the end of a car. Fig. 21 is a central longitudinal section of my water-tight 75 coupling, and showing a portion of a clasp wherewith it is fastened to an air-brake hose. Fig. 22 is a side elevation of the same. Fig. 23 is an end view of the same. Fig. 24 is a 80 view of two couplings made water-tight, showing connecting-wires and the mode of mounting upon a coupled air-brake hose. Fig. 25 represents an end portion of a car-sill and truck, an alarm, and means for electrically 85 operating the same. Fig. 26 is a side elevation of the alarm mechanism, its housing being shown open. Fig. 27 is an end view of the alarm mechanism, the housing and a releasing-plug of the same being shown in section. Fig. 28 is a detail view of the releasing-plug and a sectional view of its bearings in the housing. Fig. 29 is a side elevation of a European car provided with my circuit-closer. Fig. 30 is a central horizontal section 90 of the circuit-closer and its water-tight housing as especially adapted for use outside of a car or where exposed to weather. Fig. 31 is a front view of the circuit-closer and a section of its housing. Fig. 32 is a view of the 95 100

two connected sliding portions of the coupling as they appear when detached from the cars. Fig. 33 is a view of the same as arranged and attached between two cars.

5 The letter A in the drawings represents a battery, B an electric gong, X conducting-wire, C a locomotive, D tender, and E car. The battery A is secured in a box, a, as shown in Fig. 2, and this box is suitably fastened to the outer side of the engineer's cab c of a locomotive, C, as shown in Fig. 1. The box a is represented with parallel flanges a', which are made to fit parallel ordinary dovetailed bars, a'', on the side of the cab c, and thus the battery-box is held in place. Other modes of fastening (and other locations) may of course be adopted to hold the battery in place.

15 The gong B is of ordinary construction, and is connected to one of the poles of the battery and to one of the continuous wires X of the signal apparatus, as seen in Figs. 1 and 2. From there the conducting-wires are turned down to the under side of the locomotive-platform and inclosed together in an ordinary non-conducting rope-covering, X'. The rope X' is attached to the lower portion of the tender-flooring, as seen, and is turned up along the back of the tender D to a spring-clasp, d, at the head of a staff, d', on the tender. From 20 there the rope X' extends to the car E, to which it is attached by means of a coupling, F. This coupling consists of two separable parts, F' F'', the one, F', being attached to the car above the car-door, and the other, F'', to the end of the rope X'. The part F'' consists of a non-conducting solid cylinder, f, into which the end of the rope X' is secured, and to the end portion of which two cylindrically-curved conducting or metal plates, f' and f'', are secured at a suitable non-conducting distance from each other.

25 Between the plates f' and f'' and the cylinder f the wires X are located, which for a suitable distance are deprived of their coverings and are bent outwardly in order to touch the said plates and transmit their currents to them. The plates f' f'' are each provided with a slot, f³, flaring at its outer termination, by which they are secured to the part F', as will be seen. Each plate f' and f'' is also provided with a lateral lip, f⁴, serving as a circuit-closer, as will be presently described.

30 The part F' consists of a non-conducting flanged plug, f⁵, to the flange f⁶ of which the radial flanges f⁷ of two semi-cylindrical conducting-plates, f⁸ f⁹, are suitably fastened. The plates f⁸ f⁹ inclose the plates f' f'' when the coupling F' is connected, and they are separated at suitable non-conducting distances, 35 like plates f' f'', and the four plates are arranged in pairs, as f' f⁸ and f'' f⁹, separate from each other, so as not to close the circuit. The plates f⁸ f⁹ are provided with notches f¹⁰ opposite the lips f⁴ of the part F' of such size 40 as to prevent the uniting of the positive and negative currents, and thus render the mo-

mentary closing of the circuit impossible, while the coupling is in perfect connection.

45 The perfect connection is effected by means of the above-mentioned slots f³ of part F' and two spring-clamps, G, of part F'. The spring-clamp G consists of a semi-spherical clamp-head g inside the part F', a straight shank, g', passing through the conducting-plates f⁸ and f⁹, a spring, g², outside of the conducting-plate, surrounding the shank and bearing against the conducting-plate and a head, g, of the clamp G. In connecting the coupling the part F' is inserted into the part F', the slots f³ being held in line with the clamps G. The clamp-heads g are easily moved upon the advancing plates f' f'', and the shanks g', coming in contact with the termination of the slots f³, check any further advance of the part F', which is thus properly connected with part F', as seen in Figs. 5, 6, 7, and 8. When the connection of the coupling is imperfect, as indicated by dotted lines in Fig. 5, the lips f⁴ are in contact with the previously-insulated plates f⁸ f⁹, and thus close the circuit of the train 50 and set the gong B in operation. Each end of a car is thus provided with a coupling F, and the two coupling parts F' F'' are connected by means of their conducting-wires X X, which are attached to the ceiling of the car, as seen 55 in Fig. 1, or to any safe and convenient part of the car. With this construction the bell-rope circuit-closer H is connected by means of branch wires X² X². The bell-rope I, of ordinary construction, is stretched through the 60 car and secured thereto by means of handles i. These handles i are slotted, as at i', and provided with clamp-screws i², so as to securely clamp and adjust the bell-rope I, which may be held at the desired angle by 65 means of an inclined groove, i³, in each of the clamping-surfaces of the handle. This groove, being nearly midway between the upper and lower ends of the handle, causes the handle to stand across the opening in the car through 70 which the bell-rope passes, and prevents the upper end being drawn into said opening by a hearty pull on the bell-rope. The bell-rope is severed at or about the middle and connected by means of hooks h to eyes or hooks 75 h' h'' of its circuit-closer H, as shown in Fig. 10. This circuit-closer consists of an oblong frame formed by non-conducting bars h³, conducting end braces, h⁴, and a conducting bridge-plate, h⁴, having a central insulator, h⁵. A 80 conducting-rod, h⁶, having the hook h on its outer end and a transverse head, h⁷, on its inner end, passes through one of the braces h³ and the insulator h⁵ of the bridge-plate h⁴, and is provided with a fixed collar, h⁸, at the other 85 side of the insulator. Between the brace h³ and the collar h⁸ a spring, h⁹, is so inserted as to hold by its tension the collar h⁸ against the insulator h⁵. Between the head h⁷ and the bridge-plate h⁴ the head h⁷ is provided with a 90 short conducting-spring, h¹⁰, which, when the rod h⁶ is pulled by the bell-rope, approaches 95

and touches the bridge-plate h^4 , and thus closes the circuit by means of the branch wires $X^2 X^2$, which are connected one between the fastening and surface of the brace h^3 , and the other to the conducting fastening of the bridge-plate h^4 .

In Fig. 14 I show a simplified construction of the bell-rope circuit-closer, which consists of a non-conducting head, h^1 , provided with two insulated conducting flat springs, h^{12} , having direct connection with the branch wires $X^2 X^2$ and pull-hooks h^{13} , conducting-rod h^6 , insulator h^5 , head h^7 , with short conducting-spring h^{10} , similar to the one previously described, the one end of the rod being fastened to the spring h^{12} opposite the insulator h^5 , thus dispensing with spring h^9 , above described.

In the modification shown by Figs. 15, 16, and 17 I dispense with the ceiling-wires $X X$ and branch wires $X^2 X^2$, and conduct my wires $X X$ through an inclosing non-conducting pull-rope, X' , to an expandable frame consisting of conducting parallel plates h^{14} , fastened to non-conducting plugs h^{15} and coupled by springs h^9 . A rod, h^6 , is fastened to a lug, h^{17} , of one of the plates h^{14} , and passes through the plugs h^{15} and through a lug, h^{18} , of a plate, h^{14} , on the other side of the circuit-closer, so that lug h^{17} and rod h^6 are connected with the positive pole of the open circuit. The lug h^{18} , having a wide insulation-opening, h^{19} , through which the rod h^6 passes, permits this rod to pass without having the slightest electric communication with the lug. The rod h^6 is provided with a head, h^7 , and a spring, h^{10} , of such diameter as to come in contact with the lug h^{18} when the rod is moved toward it by pulling the bell-rope I , thereby closing the circuit. The plates h^{14} are provided with angular notches h^{20} , having a contracted or tapering horizontal termination, as seen in Fig. 16. Into these notches transverse pins i^4 of the rope-couplings i^5 are inserted, whereby the conducting bell-rope becomes attached to the circuit-closer. The pins i^4 are fastened or formed on parallel conducting-plates i^6 , which are fastened to non-conducting plugs i^7 and are made to fit snugly between the plates h^{14} . The plugs i^7 are provided with central holes for the reception of the circuit bell-rope X' , the wires $X X$ of which are turned outwardly and suitably connected with their respective conducting-plates i^6 , as shown in section in Fig. 16. The bell-rope X' is in this case connected with the outer permanent portions of couplings F , in the manner seen in Fig. 17, and the handles i are fastened to it, so as to give it the requisite tension inside the car.

Figs. 18 and 19 show a circuit-closer, K , of similar principle to Fig. 10—viz., the sliding insulated conducting-rod h^6 —as applied to a freight-car and worked from the roof of the same. The rod is hung in two conducting-brackets, k k' , suitably connected with the branch wires $X^2 X^2$. The bracket k' is provided with an insulator, h^8 , through which the

rod passes. The rod h^6 is provided with a collar, h^9 , a head, h^7 , and a conducting-spring, h^{10} , which latter touches the bracket k' and closes the circuit when the rod h^6 is pulled up. 70 The rod h^6 is kept down in its normal position, as shown, by a spring, h^9 , which causes a suitable tension between the bracket k and collar h^9 . The end portion of the rod h^6 is suitably connected to a chain or rod, k^3 , which moves 75 in a guide-bracket, k^4 , and is fastened to a water-proof cap, k^5 , fitted snugly to the upright cylinder k^6 on the roof e of the car.

The cap k^5 is provided with a suitable handle or button, by which it is pulled up in order to close the circuit below, as described. A spring, k^7 , of powerful tension, is hung to the rod k^3 between the guide-bracket k^4 and upper end portion of the rod h^6 in such manner that its tension begins to operate as soon as the rod h^6 has closed the circuit by very perceptibly increasing the resistance offered to the continuation of the upward motion, which serves as a warning to the operator on the car-roof that the circuit is closed and the 90 desired signal given to the engineer of the train.

I have found that a coupling and circuit-closer combined and suitably secured to the old bell-rope eyes at the ends of the car, as shown in Fig. 20 by letter L , is the most economical and convenient for special cars. The coupling portions $F' F^2$ are of the same construction as described in respect to Figs. 3, 4, 5, 6, 7; but the flanged portion f^6 is further 100 provided with two conducting-springs, h^{10} , suitably connected with the plates $f^8 f^9$. A tube, l' , containing the conducting pull-rope X' , is by means of a flange, l^7 , fastened to the flanged portion f^6 of the non-conducting plug 105 f^5 . The wires $X X$ are at the ends of the rope X' turned toward the plates $f^8 f^9$, respectively, thus making the connection with the coupling. The tube l' is placed in a tube, l^3 , provided with an outer flange, l^4 , and an inner 110 flange, l^5 , through which latter the tube l' slides, which at that point is provided with an outer flange, l^6 . A spiral spring, l^8 , is placed around the tube l' and between it and the tube l^3 , which spring bears against the flange l^5 of 115 the tube l' and the flange l^6 of the tube l^3 , and thus keeps the springs h^{10} at the proper distance from the flange l^4 , while the flange l^6 prevents the tube l' from being moved too far forward. The tube l^3 is provided with flat longitudinal curved springs l^8 , which allow the said tube to be inserted into the bell-rope eyes e' of the car end e^2 and hold it there firmly in a central position. When the rope X' is pulled, the tube l' and coupling F are moved 120 toward the car until the springs h^{10} come in contact with the metallic conducting-flange l^7 , thus closing the circuit and giving the signal.

In Fig. 21 the coupling F is shown provided with a water-proof casing, M , and a 130 cap, m , connected with it by means of spiral springs m' , which hold the cap upon the cas-

ing when open, as shown in full lines, or hold the cap securely in place while closing the casing, as shown in dotted lines in Fig. 22. The casing M is fastened to the plug f^5 of the coupling portion F' , and the plug f of the coupling portion F^2 is made large enough to fit the casing M, and is also provided with a rubber packing, m^2 , secured in an annular groove of the plug, as shown. The water-proof coupling is used outside of the car and may be attached to the hose Y of an air-brake, in which case it will be provided with a hinged clasp, m^3 , of ordinary construction, which is made to hug the hose, or when said coupling is to be fastened to a straight or plain surface one or two ordinary flanges and screw-bolts will serve the purpose.

When a special signal is desired, whereby the engineer is notified of any damage to a car—such as derailing of a truck or the breaking of a wheel or axle—I combine my invention, as described, with an alarm-wheel, n , of a clock mechanism, N, set in motion by means of the removal of a stopping-plug, n' , connected by a chain, n^2 , with the truck n^3 of a car, as shown in Figs. 25, 26, 27, 28. A circuit-closing spring, n^4 , comes in contact with the teeth of the wheel n , and so produces the special alarm. This special mode of giving an alarm forms the subject-matter of another application filed on an even date with this and numbered 240,779. I merely illustrate it as being adaptable to trains provided with my present invention.

The circuit-closer shown in Figs. 18 and 19 may be inclosed in a water-proof housing and used outside of the car, as shown in Figs. 30 and 31. The housing shown there consists in a metallic shell, O, having an open back and a flange, o, around the same, which latter is fastened to a wooden back, o'. Between the flange o and back o' a soft-rubber packing, o², is interposed-making a water-tight joint.

The circuit-closer proper is of the same construction as the above-described, only the spring k^5 and water-proof cap k^6 being omitted. This circuit-closer is operated by means of cords I, running on the outside of the car E, as seen in Fig. 29, where it is seen fastened at e' e', and passing around guide-rollers o' o² in the housing O and upward to the rod h⁶. The operation of this circuit-closer is principally the same as that above described, the wires X X and their couplings F in this case being fastened to the car-sill, as seen.

I would prefer to use but one style of circuit-closer were it not for the mixed conditions of the trains. I would prefer Fig. 10 for use in all cases, as I have shown it for ordinary passenger-cars where the car is free from partitions, and I am at liberty to fasten the wires to the ceiling of the car. Fig. 15 I prefer to use in sleeping or other cars which have numerous partitions in them. By using a cable rope with two wires therein connected with the circuit-closer, as illustrated in Fig. 15, it is unnecessary to mar or injure the car by

making holes suitable to run wires X X, as would be necessary if a circuit-closer like Fig. 10 were used. Fig. 20 is especially designed for use on special cars which are not provided with my permanent electrical appliance. The special or visiting car from some foreign road may be placed at any point in the train, and a section of rope and connector and circuit-closer, as shown in Fig. 15, can be run through the car same as any ordinary bell-rope, and being connected to the proper connector or coupling on the car ahead, and in the rear the circuit is conveyed through the train. If I did not make these provisions, as above noted, my invention could not be used in such a manner as would develop all of its utilities in mixed trains, and therefore these variations of construction and form I find necessary for a perfect working of my appliance on cars of all classes brought together in a train.

I do not claim under this patent the special construction and combination shown by Figs. 20 and 29 of the drawings, as I have on March 10, 1888, Serial No. 266,786, filed a separate application for a patent therefor.

What I claim as my invention, and desire to secure by Letters Patent, is—

1. The combination, with the pull-rope extending from end to end of the respective cars of a train and having an electrical signal apparatus combined therewith, of the pendent non-conducting handles i, provided with the slots i', grooves i², and clamp-screws i², substantially as and for the purpose described.

2. The coupling F, comprising sections F' F², and having the plates f⁸ f⁹, having spring-clamps G, and the plates f' f², having slots f³, substantially as and for the purpose described.

3. The coupling F, comprising sections F' F², and having the plates f⁸ f⁹, with notches f¹⁰, and the plates f' f², with lips f⁴, substantially as and for the purpose described.

4. In the circuit-closer H, the conducting-rod h⁶, having contact-spring h¹⁰ and tension-spring h⁹, conducting-braces h³ h⁴, insulator h⁵, branch conducting-wires X X², and pull cord or rope, substantially as and for the purpose described.

5. In a manual electric-circuit closer for signals for railroad-trains, the combination of the pull-rope, electric conductors or circuit-wires, circuit-closing reciprocating rod, circuit-opening tension-spring, and cylindrical spiral-spring contact device applied on the said reciprocating rod and against a head, h⁷, thereof, substantially as and for the purpose described.

6. In an electric train-signaling apparatus, the combination of the coupling portion F', having housing M, springs m', and cap m, with the coupling portion F², having rubber packing m², substantially as and for the purpose described.

7. In an electric alarm signaling apparatus provided with a coupling and circuit-closing mechanism, the spiral-spring contact device

h¹⁰, and making a direct contact itself with the contact-plate, and arranged upon a reciprocating conducting-rod, *h⁶*, which is insulated by a bushing of the contact-plate, against which (the plate) said spring-contact bears when the circuit is closed, substantially as and for the purpose described.

In testimony whereof I affix my signature in presence of two witnesses.

JOHN RICHARD DE MIER.
